UNITED STATES PATENT OFFICE

2,303,649

STABLE CLEANER

Eugene A. Livingston, Cass City, Mich.

Application October 24, 1940, Serial No. 362,526

2 Claims. (Cl. 37—120)

This invention relates to a stable cleaning device, and more particularly to a power actuated litter fork for operation in the stable gutters for quickly, easily, and efficiency cleaning said gutters.

One of the prime objects of the invention is to provide a hinged litter fork of substantial construction which can be readily and easily handled, and which can be automatically tripped to allow the tined portion of the fork to swing downwardly and positively dump the load.

Another object is to design a litter fork of simple and practical construction which is easy to manufacture and assemble, which readily slides in the gutter, and which is automatically locked in set operative position when the tines are swung back to original position.

With the above and other objects in view, the present invention consists in the combination and arrangement of parts, hereinafter more fully described, illustrated in the accompanying drawing, and more particularly pointed out in the appended claims, it being understood that changes may be made in the form, size, proportions, and minor details of construction, without departing from the spirit, or sacrificing any of the advantages of the invention.

In the drawing:

Fig. 1 is a sectional, side elevational view of a building showing stables and gutters with my improved fork in position thereon;

Fig. 2 is an enlarged, side elevational view of the litter fork, the broken lines showing the fork tines swung down for unloading; and,

Fig. 3 is a top plan view.

Fig. 4 is a fragmentary edge elevational view showing the back and push plates hinged together and the bracket in position on the back plate.

Dairy buildings in general are designed with gutters located directly in the rear of the stable proper and in which straw, refuse, etc., collects. Ordinarily, the cleaning of the gutters is done manually with a fork, the contents being carried to a refuse pile or bed located outside the building proper. This cleaning is a somewhat slow and tedious operation, and I have therefore designed a litter fork and attachment, power actuated and controlled, so that the manual labor is eliminated, and whereby the refuse is pushed to a spreader vehicle or to a pile located adjacent the stable proper, and from which it can be handled as desired.

Referring now more particularly to the drawing, the numeral 8 indicates a building of con-

ventional design such as used to house cattle, horses, and other animals. A trough or gutter 9 is provided in the floor of the building as shown, and an upwardly inclined extension 10 is provided outside the building and forms an extension of the stable gutter proper, the upper end being elevated sufficiently so that the refuse can be discharged into a spreader vehicle 11 for transportation to any desired location.

10 The litter fork F is formed as clearly shown in Figs. 2 and 3 of the drawing, and comprises spaced apart push and back-plates 12 and 13 respectively, hingedly connected together at the point 14, and a centrally disposed draw bar 15 which is secured to the back-plate 13 by means of rivets or the like (not shown), the free end extending forwardly, and one end of a cable member 16 which is secured thereto, so that the fork can be drawn along the gutter when in use.

15 Spaced apart, rearwardly extending, upwardly curved members 17 are also secured to the plate 13 and form a shoe, the outer ends of said members being bolted to a transversely disposed bar 18 by means of bolts 19. A bar brace 20 is rigidly secured to the draw bar 15 and to the bar 18 to form a rigid structure.

20 Spaced apart tines 21 are provided on the push-plate 12, the free ends being pointed so that they readily lead into the refuse, these tines being drawn in said gutter beneath the refuse to hold the fork in position in the gutter.

25 A rearwardly extending bracket 22 is mounted on the back face of the plate 13, and an L-shaped latch lever 23 is pivotally mounted thereon by means of the bolt 24, the forward end of said latch lever being notched as at 25 to engage the upper edge of the plate 12, the opposite end being turned upwardly as shown at 26 for engagement by a suitable stop 27 provided at the outer end 40 of the trough extension, so that the plate 12, together with the tined section of the fork, is automatically released as the fork is drawn to its discharging position.

30 A spring 28 is anchored to the latch 23 and to the back-plate 13 respectively, for swinging the latch back to original position after it has been tripped, and a curved rod 29 is anchored in the plate 12, thence projecting rearwardly and serving as a track or guide to insure against binding when the fork is opened and closed.

35 One end of an endless cable 16 is connected to the end of the draw bar 15, thence leading to the sheave 30, thence around a sheave (not shown) provided beyond the end of the trough 10, thence being wound on the drum D as usual, thence the

cable leads back and over the sheaves 31 and 32, and thence being anchored to the cross bar 18 provided on the fork, so that the fork can be hauled rearwardly as well as forward, and this drum is, of course, power driven; but this forms no part of the present invention which is broadly directed to the fork proper.

The motor (not shown) is remotely controlled from a switch held in the hand for starting, stopping, forward, or reverse as desired. In practice, the fork is placed in the gutter with about twenty linear feet of refuse ahead of it, then as the fork is drawn forward, it pushes the refuse up the inclined trough 10 and onto the spreader 11, and as the fork travels forwardly the latch 24 is tripped by the stop 27 after which the operator reverses the direction of travel, the tined section then swings back to horizontal position and is latched, and the fork is then brought back to position to again push another section of refuse in the same manner, the operation being repeated until the gutter is entirely cleaned.

From the foregoing description, it will be obvious that I have perfected a very simple, practical, and economical litter fork for cleaning stable gutters and the like.

What I claim is:

1. A litter fork comprising a flat back-plate provided with rearwardly extending, upwardly curved bar members forming a shoe; a forwardly extending draw bar secured to said plate, an imperforate push-plate hingedly connected at its lower edge to said back-plate, spaced apart tines provided on and projecting forwardly from said push-plate, a spring tensioned latch mounted on said back-plate and engageable with the push-plate, and a guide rod mounted on the push plate and slideable in said back plate.

2. A litter fork comprising a back plate provided with rearwardly extending, upwardly curved bar members forming a shoe; a forwardly extending draw bar secured to said plate and connected to said shoe; an imperforate push plate hingedly connected at its extreme lower end to said back plate; spaced apart tines connected to the lower edge of the push plate, and extending forwardly therefrom; latching means mounted on said back plate and engageable with the push plate, and a guide rod mounted on the push plate and slideable in said back plate.

EUGENE A. LIVINGSTON.
